UNITED STATES PATENT OFFICE.

J. HYDE FISHER, OF CHICAGO, ILLINOIS.

IMPROVEMENT IN LATCHES.

Specification forming part of Letters Patent No. 123,817, dated February 20, 1872.

Specification describing a new and Improved Lever-Latch and Handle, invented by J. HYDE FISHER, of Chicago, in the county of Cook and State of Illinois.

Figure 1 represents my improved latch and handle as attached to the doors of a refrigerator, one of the doors being represented as closed and the other as open. Fig. 2 is a detail sectional view taken through the line x x , Fig. 1.

Similar letters of reference indicate corresponding parts.

My invention has for its object to furnish an improved lever-latch and handle, designed especially for refrigerator-doors, but which may be used with advantage upon closet and other doors, and which shall be so constructed as to take up the wear, holding the door at all times tightly closed; and it consists in the construction and combination of the various parts of the device, as hereinafter more fully described.

A represents the bar which forms the latch, and which is pivoted at or near its middle part to the door to be fastened, in such a position that its forward end may enter the catch attached to the door-post or casing at the side of the door. B is the handle, which is formed upon the latch or bar A, and which is made shorter than the said bar or latch, so as to be eccentric as regards the bar or latch A, thus making the inner end of the latch and handle A B heavier, so that when unlatched the latch and handle will take a vertical position, as shown in Fig. 1, and not be liable to strike against the catch should the door be accidentally closed. Upon the lower part of the plate or disk C, through which the pivoting-screw of the latch and handle A B passes, is formed a stop, c', to prevent the latch or handle from swinging around too far or into a reversed po-

sition. To the door-post or casing, at the side of the door, is attached a plate, D, having a projecting rib or flange, d¹, formed upon it, and in the lower part of which, at the side of the lower end of the said rib or arm d¹, is formed a recess, d², in which is placed a rubber block, E, or other suitable spring. In the case of double doors, as shown in Fig. 1, the rib or flange d¹ is formed on the middle part of the plate D, and has a recess or socket, d², upon each side of its lower end. To the side or sides of the upper part of the rib or flange d¹ is pivoted a short bar, F, which forms the catch, and which is made with an offset upon its lower end, which enters the recess or socket d² upon the inner side of the spring E, and the shoulder of which covers and incloses the spring E. The elasticity of the spring E thus holds the lower end of the pivoted bar or catch F pressed inward, and makes the space between said bar or catch and the surface to which the plate D is attached wedge-shaped, as shown in Fig. 2. By this construction, as the latch is turned into its place it is held firmly by the spring-catch, and as it wears it only drops down a little further into the wedge-shaped cavity, into which it enters, and always holds the door tightly closed.

Having thus described my invention, I claim as new and desire to secure by Letters Patent—

The latch A, hinged bar or catch F, and the rubber block E and its holding-socket, combined substantially as shown and described, to operate as specified.

The above specification of my invention signed by me this 2d day of October, 1871.

J. HYDE FISHER.
